UNITED STATES PATENT OFFICE.

ALMERIN R. SPRAGUE, OF MILWAUKEE, WISCONSIN.

INK-WELL COVER.

SPECIFICATION forming part of Letters Patent No. 442,403, dated December 9, 1890.

Application filed April 25, 1890. Serial No. 349,478. (No model.)

To all whom it may concern:

Be it known that I, ALMERIN R. SPRAGUE, of Milwaukee, in the county of Milwaukee, and in the State of Wisconsin, have invented certain new and useful Improvements in Ink-Well Covers; and I do hereby declare that the following is a full, clear, and exact description thereof.

My invention relates to covers for ink-wells, such as are usually provided for school-desks, &c.; and my invention consists in certain peculiar and novel features of construction and arrangement, as hereinafter described, and pointed out in the appended claims.

In order that my invention may be fully understood, I will proceed to describe it with reference to the accompanying drawings, in which—

Figure 1 is a plan view of an ink-well cover embodying my invention and the adjacent portion of the top of a desk to which the cover is applied, the well-cover being in closed position. Fig. 2 is a view similar to Fig. 1, showing the cover in open position. Fig. 3 is a transverse vertical section on the line 3 3 of Fig. 1. Fig. 4 is also a transverse vertical section on the line 4 4 of Fig. 2. Fig. 5 is a transverse vertical section of the cover on the line 5 5 of Fig. 2. Fig. 6 is a horizontal cross-section of the stem of the cover on the line 6 6 of Fig. 3. Fig. 7 is a view similar to Fig. 3, but illustrating a modified embodiment of my invention. Fig. 8 is a rear elevation of the cover shown in Fig. 7.

The objects of my invention are to produce a cover for the ink-wells of school-desks which shall be inexpensive and very durable in construction, and which when closed shall without the aid of packing effectually exclude dust and dirt from the well and completely avoid evaporation of the ink. Furthermore, to produce a cover which shall open and close noiselessly, and which shall be accurately flush with the top of the desk when closed; also to prevent any liability to accidental breakage of the cover when either open or closed, and to render the cover easier to close than to open, so that it shall usually remain closed, and at the same time to facilitate the

proper opening of the cover when access to the ink is desired.

It is well known to teachers and others engaged in similar work that the ink-well covers heretofore provided for school-desks have been seriously defective and have occasioned much annoyance by reason of their noisiness in opening and closing, their liability to be left open by the pupils and to consequent injury and rapid destruction by contact with the books and other articles upon the desk, and the rapid waste of ink by evaporation as well as its spoiling by the admission of dust and dirt to the ink. These defects are especially noticeable in the hinged types of well-covers, and are by no means obviated by any forms of laterally-swinging covers produced previous to my present invention. As will be seen, I entirely overcome these defects by virtue of the construction which I will now proceed to describe.

In the drawings, A designates that portion of the top of a school-desk which contains the aperture a, in which the usual ink-well B is supported, so as to depend below the top of the desk. This aperture is preferably, although not necessarily, of the usual circular form adapted to sustain a cylindrical well, although a square or other form of well may be employed, if desired. In any event the arrangement is such that the upper portion of the well is depressed below the level of the top of the desk, this result being usually accomplished by countersinking the top of the well into the aperture. At one side of this aperture is formed a vertical opening or socket C, which is circular in cross-section and extends completely through the top of the desk, the axis of the socket being parallel with the axis of the aperture a, before described. The upper end of the socket C is connected with the upper part of aperture a by a groove or elongated recess D, which is formed in the upper surface of the top A and extends laterally from the socket C, as shown.

E designates the cover, which is preferably of the circular or disk form shown to correspond with the circular contour of aperture a, but which may obviously be of square,

oval, or other form to correspond with similarly-varied forms of such apertures. At one side of this cover is cast a short integral radial extension *e*, the under side of which is 5 convex, as shown at *e'*, for a purpose to be presently explained. At the outer end of this extension *e* is cast integrally a cylindrical stem *F*, which extends downward from and at right angles to the said extension *e*. 10 The length of this stem is perceptibly greater than the length or depth of the opening or socket *C*, so that the lower end of the stem projects considerably below the lower end of the socket, or at least a distance somewhat 15 greater than the vertical thickness of the convex part of the extension *e*.

As shown in Figs. 3 and 4, the lower extremity of the stem *F* is reduced, as shown at *f*, to enter an eye in a square or angular plate 20 *G*, the lower end of said reduced portion being upset or formed into a head to retain the plate in position.

The structure shown in Fig. 7 is in all respects similar to that above described, with 25 the exception of the stem *F*. In this instance the angular plate *G* is dispensed with and the lower end of the stem is flattened, as shown at *H*. After the stem has been inserted into the socket *C* the flattened portion *H* is bent 30 from the straight form shown in dotted lines to the curved form shown in solid lines, the stem being preferably of malleable iron, so as to permit this bending to be readily effected. This bent portion *H* preferably projects from 35 the stem *F* in a line at right angles to the extension *e*, as shown, for a purpose to be presently explained.

The manner of using and manipulating the above-described structure is as follows: Assuming the cover to be in the position illustrated in Figs. 1, 3, and 7, the hand is thrust 40 into the desk and a finger is applied beneath stem *F* to lift the latter. This raises cover *E* off from the cavity *a* and lifts the concave portion *e'* out of the groove *D*. By now slightly crooking the finger a lateral pressure 45 can be exerted upon one of the sides of the plate *G*, which causes the cover *E* to swing laterally away from aperture *a*, the stem *F* 50 acting as a pivot. During this swinging movement the concave portion *e'* glides easily upon the top of the desk without marring the same, and also prevents the under side of cover *E* from coming into contact with the 55 top and daubing it with ink. This latter office of the concave portion *e'* also continues as long as the cover remains open. By virtue of the peculiar direction of the bend *H* in Fig. 7 relative to the direction of extension of 60 the cover from the stem *F* the lateral pressure of the finger is facilitated in swinging the cover open, as described. In order to close the well, the cover *E* itself is directly manipulated so as to move toward the aperture *a*, 65 into which it will fall by gravity, as will also the convexity *e'* into its groove *D*. When

the cover is in closed position, it lies flush with the upper surface of the top of the desk, and is thus effectually protected against injury by violent contact with books or other 70 articles on the desk, and when open any such contact will simply close the cover without injuring it. The cover cannot be pulled out of place either when open or closed, and it is entirely noiseless in its action. When closed, 75 the cover effectually excludes dust and dirt from the well without the aid of packing; but it is obvious that packing may, if desired, be used without departing from the essential spirit of my invention. Furthermore, it will 80 be seen that as the cover is more easily closed, either intentionally or accidentally, than it is opened (although the latter is by no means a difficult operation) it will usually be found closed, except when the ink is being used, and 85 thus the ink will be constantly protected against evaporation, and dust will also be constantly excluded.

While I have described my invention as applied to school-desks, to which it is peculiarly 90 adapted, it is obvious that it can be with equal efficacy applied to office-desks and writing furniture generally without involving any departure from the essential spirit of my invention.

Having thus described my invention, what I claim as new therein, and desire to secure by Letters Patent, is—

1. An improved cover for ink-wells, comprising a covering-plate and an elongated 100 stem formed integrally therewith and extending downward therefrom and constituting the sole pivot for the cover, substantially as described.

2. An improved covering for ink-wells, comprising a covering-plate, an extension projecting laterally from said plate and having a convex under side, and a stem or pivot extending downward from the outer end of the 105 extension, substantially as described.

3. An improved cover for ink-wells, comprising a covering-plate, an extension projecting laterally from said plate and having a convex under side, and a stem or pivot extending downward from the outer end of the 110 extension and provided at its lower end with a finger-piece, substantially as described.

4. The combination, with a desk-top having an aperture to receive an ink-well, a vertical opening or socket, and a groove connecting the upper end of the socket with the aperture, of a well-cover comprising a covering-plate, an extension projecting laterally from the covering-plate and having a convex under side, and a stem or pivot extending downward from the outer end of the extension and having a finger-piece at its lower end, substantially as described.

5. The combination, with a desk-top having an aperture to receive an ink-well, and a 130 groove extending laterally from said aperture, of a cover comprising a plate to fit the

aperture and a lateral extension having a convex under side, whereby the cover and its extension shall lie flush with the top of the desk when the cover is closed, and whereby, 5 also, the cover shall be held up out of contact with the desk-top by the convex portion when the cover is open, substantially as described.

In testimony that I claim the foregoing I have hereunto set my hand, at Milwaukee, in the county of Milwaukee and State of Wisconsin, in the presence of two witnesses.

ALMERIN R. SPRAGUE.
